DUMP CAR DOOR LOCK

Jay R. Sheesley, Winnetka, Ill.

Application October 16, 1946, Serial No. 703,514

5 Claims. (Cl. 105—308)

1

My invention relates to a single acting lock for the drop bottom door of a railway dump car and has for its object the provision of a simple and easily operated structure capable of effecting a positive and complete closure of the door and controllable from the side of the car. The invention also contemplates a structure which permits the released downwardly hanging door to be swung toward closed position where the locking mechanism will automatically effect holding engagement with the door; all of the operations being effected by the operator standing in a safe zone at the car side.

My present invention relates to the type of door locking mechanism shown and described in my application Serial Number 632,456, now abandoned, and its object and advantages will be readily comprehended from the following detailed description of the accompanying drawings wherein—

Figure 1 is a sectional view of a portion of a hopper of a railway dump car and the hopper door with my improved door locking mechanism in sectional elevation.

Figure 2 is a similar view of the lower end of the hopper and door with the locking mechanism in elevation and door released position with the door partly open.

Figure 3 is an elevational view of the lower portion of the hopper with the hopper door omitted.

Figure 4 is a detail sectional view taken substantially on the line 4—4 of Figure 1 as indicated by the arrows.

Figure 5 is a detail perspective view of the locking pawl or latch member supporting end of the control shaft.

Figure 6 is a detail view of the outer end of the control shaft, its operating handle and shaft locking mechanism in elevation and a portion of a hopper wall in section, with portions of the hopper frame shown in dotted lines.

Figure 7 is a perspective view of the movable latch member in inverted position.

Figure 8 is a sectional view on a larger scale of the lower portion of the dump car hopper and lower end of the door in open position with my improved door locking mechanism in door releasing position.

Figure 9 is a similar view showing the hopper door completely closed, with the locking mechanism in door locking position.

Figure 10 is an exploded perspective view of the eccentric and lug portion of the operating shaft and of the latch member positioned to receive the adjacent eccentric end of the shaft.

2

My present invention is especially adapted to the single operation of the respective downwardly swing doors of the different hoppers arranged on opposite sides of the car center sill, but of similar construction, with similar control and locking mechanisms controllable at the car sides.

In the exemplification of the invention the latch member or locking pawl and the control shaft are mounted on the lower side of the hopper slope sheet, of which a portion is shown at 10, where it will not interfere with the free flow or dumping of the hopper contents and does not apply added weight to the door of which a portion is shown at 11. The door is pivotally mounted at its upper end in the usual manner to swing downwardly into open position as soon as the latch mechanism is released, see Figure 2.

The door preferably is formed or flanged at its perimeter to overlap the edges of the slope sheet to provide a non-leak relation and adjacent its lower end preferably reinforced by the angle member 12, which also provides means for rigidly securing latch or keeper member 13 in place.

The lower end 14 of latch member 13 extends forwardly into a socket formed into the door or through a cut-out portion or slot, as shown, in the lower end of the door 11; and this forwardly presented end on its lower side is provided with a transverse rib 15 with which a locking pawl or latch member 16 is adapted to effect latching engagement.

The latch member 13 preferably is arranged intermediate the side edges of the door and its forward end formed with a sloping or slightly arcuate surface adapted to ride over and force the latching end of the locking pawl or latch member 16 downwardly when the door is swung to closed position.

The lower end of the slope sheet 10 preferably is reinforced with a transversely extending angle 17 which also affords attaching surface for the elongated transversely extending bearing providing bracket plate or strip 18, provided at its inner end with longitudinally spaced ribs or flanges 19, 20 and adjacent its outer end with an apertured flange or rib 21; the outer end of the bracket plate or strip being shown sloping or bent upwardly in keeping with the edge of the side wall of the hopper.

The flanges or ribs are apertured to receive and provide bearings for the ends of the latch operating shaft 22. By providing a single bearing plate or strip it is apparent that a proper and positive alignment of the bearing flanges or ribs is ensured and the operation of properly attaching more

readily accomplished and alignment maintained.

The outer end of shaft 22 is provided with a socketed and angularly disposed handle portion 23, whose socket is adapted to receive a suitable sized bar or lever employed by the operator in door operations.

Secured to or formed integral with the bracket plate and disposed above the shaft bearing is a bracket portion 24 on which a segmental locking cam 25 is eccentrically pivoted to effect wedging engagement with the side of the handle portion 23 when shaft 22 and the handle portion 23 have been rotated into door latching position, see Figure 6. The cam 25 preferably is counterweighted as shown to maintain its shaft locking position; and as the cam rotates in a direction transversely of the car its shaft locking position will not be disturbed by the jars and vibrations encountered by the car during transit, as such vibrations are principally transmitted longitudinally of the car.

The shaft 22, adjacent its inner end, is formed or provided with an eccentric portion 26 and with a segmental lug 27 of preselected dimensions and in prearranged relation to the eccentric portion 26; the ends of the lug 27 preferably having flat surfaces as more clearly shown in Figure 5. The lug 27 extends radially adjacent the end of the eccentric portion 26, substantially in line with the major axis of the eccentric portion 26.

The inner end of shaft 22 is shown of normal diameter and has bearing in the flange 20 and may be held against withdrawal by a suitable cotter-pin as at 28, in Figure 4.

The shaft 22 at one end of the eccentric portion and adjacent the lug 27 is provided with an annular flange or collar portion 29 to afford a proper bearing for the shaft in the enlarged opening in flange 19; the enlarged opening being provided to permit passage of the eccentric portion 26 and lug 27 therethrough. The eccentric portion 26, segmental lug 27 and collar 29 may all be made integral with the shaft 22. Freely mounted on the eccentric portion 26 is the locking pawl or latch member 16 whose forward or rearward movement relative to the latch member 13 secured to the swinging end of the door 11 is controlled by the eccentric portion 26 during rotation of the shaft 22; that is to say, the locking pawl 16 during this rotative cycle of the eccentric portion 26, due to its counterweighted end 16^a, does not rotate but shifts in the direction of the eccentric portion relative to the discharge end of the slope sheet 10, namely toward or away from said discharge end.

The hub portion of the latch pawl 16 has a segmental extension 16^b disposed in the path of the lug 27, with the relation between the lug 27 and the ends of the segmental hub extension 16^b such that contact between the lug 27 and extension 16^b is not effected until the eccentric portion 26 of the shaft has substantially completed its shifting action of the latch pawl 16.

Assuming that the drop door 11 is in closed position with pawl 16 in locking engagement with the rib 15 of latch member 13, the forward shifting action of eccentric 26 will move pawl 16 forwardly without moving the hook end of the pawl 16 out of engagement with the keeper member 13 on the door but permit the door to partly open. The continued rotation of the shaft in clockwise or same direction, for example approximately one hundred and thirty degrees, will bring one end of the segmental lug 27 into contact with the segmental portion 16^b of the pawl 16 and cause the pawl to rotate with operating shaft 22 and to dis-

engage the latch member 13 of the door 11 and allow the door to swing into open position.

When the operator releases his operating bar or lever inserted in the socketed laterally offset handle portion 23, namely after the door has been opened, the latch member 16, due to the counterweight 16^a, and contact between the opposite end of segment 16^b and lug 27, will rotate the shaft 22 in a counterclockwise direction thus bringing the latch member 16 in locking pivotal position and allowing it to automatically swing into latching position and engage the latch member 13 at the bottom of the door, when the latter is swung towards the closed position. The latching pawl 16 will engage latch member 13 and hold the door within say approximately a half inch or so of full closed position. Continued counterclockwise rotation of the operating shaft by the operator causes the opposite end of the segmental lug 27 to engage the opposite end of the segmental extension at the side of the pawl 16 and induces rotation of the latch pawl 16 into door full-closing position, which position will be maintained by the counterweighted locking cam 25.

In order that the latch member 16 may be used either on the right or on the left side of the car, I show both sides of the latch member provided with similar segmental extensions 16^b; a similar operating shaft 22 being employed with an eccentric portion 26 and a lug 27, with the lug circumferentially spaced a predetermined distance from the major axis of the eccentric portion 26 so that the latch member shifting action is momentarily performed in advance of the latch member rotation induced by lug 27.

The eccentric portion 26 and the segmental lug 27 preferably are made integral with the operating shaft; the latch pawl being provided with a circular opening of diameter sufficiently large to permit it to freely swivel on said eccentric portion and for simplicity in manufacture preferably has its extended hub portion segmentally cut away to receive the segmental lug; structural modifications, however, being possible without departing from the spirit of my invention as defined by the appended claims.

What I claim is:

1. A hopper car door lock for a door whose lower free end swings horizontally comprising a rotatably mounted shaft disposed transversely of the car on the lower face of the hopper slope sheet, the inner end of said shaft having an eccentric portion and a radially disposed segmental lug; a keeper member secured to the lower side of the door; and a counterweighted hook member loosely mounted on the eccentric portion of the shaft and provided with a segmental lateral extension disposed part way about the shaft in the path of said lug, said hook member and keeper member being adapted to automatically effect door holding position when the door is swung toward closing position, said eccentric portion upon rotation of the shaft being adapted to move the hook member horizontally while further shaft rotation causes said lug to engage an end of the segmental extension of the hook member thereby moving the hook end vertically and locking the door in closed position.

2. A hopper car door lock for a door whose lower free end swings horizontally comprising a rotatably mounted shaft disposed transversely of the car on the lower face of the hopper slope sheet, the inner end of said shaft terminating adjacent the vertical median line of the hopper and its door and having a cylindrical eccentric por-

tion and a radially disposed lug substantially in line with the major axis of the eccentric portion; a keeper member secured to the lower side of the door; and a counterweighted hook member loosely mounted on the eccentric portion of the shaft and provided with a segmental lateral extension disposed part way about the shaft in the path of said lug, said hook member and keeper member being adapted to automatically effect door holding position when the door is swung toward closing position, the interengaging relation between the keeper member and hook member being adapted to withstand the outward pressure of the door, said eccentric portion upon rotation of the shaft being adapted to move the hook member horizontally while further shaft rotation causes said lug to engage an end of the segmental extension of the hook member and thereby move the hook end of the latter vertically substantially into dead center position with the eccentric portion of the shaft and thereby lock the door in closed position.

3. A hopper car door lock comprising an operating shaft disposed transversely of the car and rotatably mounted on the bottom of the hopper, the inner end of said shaft being provided with a cylindrical eccentric portion on the shaft and with a radially disposed lug arranged in predetermined circumferential spaced relation with the major axis of said eccentric portion; a stationary latch member secured on the bottom of the door intermediate its sides; a counterweighted latch pawl having a hook end and swiveled on the eccentric portion of said shaft and adapted to normally swing into latching position, said pawl being provided with a hub adapted to receive the eccentric portion of the shaft and having a laterally disposed segmental extension arranged in the path of said lug, said eccentric portion upon rotation of the shaft causing the latch pawl to move horizontally while said lug upon further rotation of the shaft causes the hook end of said pawl to swing vertically into door locking position and to move the hook end of the pawl out of engagement with said stationary latch member upon rotation of the shaft for door releasing.

4. A hopper car door lock comprising a shaft disposed transversely of the car and provided at its inner end with a cylindrical eccentric portion and with a radial lug arranged in predetermined circumferential spaced relation with the major axis of said eccentric portion; a single piece bearing member disposed transversely of and secured to the bottom of the hopper and provided with shaft bearing portions at opposite ends for rotatably securing the inner and outer ends of the shaft and maintaining alignment; a

keeper member rigidly secured to the bottom of the door adjacent its median line; a counterweighted latch member mounted intermediate its ends on the eccentric portion of said shaft and adapted to normally swing upwardly into keeper engaging position, the hub portion of said latch member at its end being provided with a laterally disposed segmental extension disposed in the path of said radial lug, the latch member being shifted forward and/or rearward by said eccentric portion and the door drawn to closed position during partial rotation of said shaft and the latch member, upon further shaft rotation, swung vertically by engagement of said lug with said segmental extension and the door locked in closed position, while reverse partial rotation of the shaft will shift said latch member forwardly, permitting partial opening of the door and further rotation of said shaft will cause said latch member to be swung downwardly out of keeper engagement; and a vertically swinging cam secured to the outer end of said bearing member so as to move in a direction transversely of the car and effect holding engagement with said shaft.

5. In a dump car provided with a hinged door whose lower end swings horizontally, door locking mechanism comprising a horizontally disposed rotatable shaft provided with an eccentric portion and a radially disposed lug arranged substantially parallel with the major axis of the eccentric portion; and a hook-ended counterweighted locking pawl loosely mounted on said eccentric portion and having segmentally arranged shoulders disposed in the path of said lug, whereby the major axis of the eccentric portion will be disposed substantially in dead center relation with the direction of the load force on the hook end of said pawl when the door is in closed position.
